CLAIM

I claim the ornamental design of a mattress mover, as shown and described.

DESCRIPTION

FIG. 1 is a perspective view of the mattress mover, showing my new design;

FIG. 2 is a top plan view thereof;

FIG. 3 is a bottom plan view thereof;

FIG. 4 is a front elevational view thereof;

FIG. 5 is a rear elevational view thereof; and,

FIG. 6 is a right side elevational view thereof, the left side elevational view being a mirror image of same.
